SELECTIVE STENCIL PRINTING APPARATUS
AND STENCIL FOR USE IN SAMEHarmon P. Elliott, Watertown, Mass., assignor to
The Elliott Addressing Machine Company, a
corporation of MassachusettsApplication December 29, 1933, Serial No. 704,440
Renewed July 6, 1936

16 Claims. (Cl. 101—58)

This invention comprises certain improvements on apparatus of the type shown in Patent No. 1,180,385 granted to Sterling Elliott, April 23, 1916, and as further modified and improved in my Patent No. 1,883,643, granted October 18, 1932, the features of construction to which the present invention relates being particularly illustrated in Figs. 4 and 5 of the latter patent. In said Patent No. 1,180,385 the selective mechanism for automatically causing the apparatus to print with, or skip each particular stencil, was designed to be mechanically actuated by said stencils which have holes punched in them for cooperation with a finger or a plurality of fingers controlling the printing devices. In my patent above mentioned similar selective mechanism was shown as being electrically actuated by a separate disc of paper having holes punched in it.

According to my present invention the selective apparatus is also electrically actuated, but this is accomplished by means of simple clips of metal or other electrically conducting material mounted on the standard forms of card stencil now in general use. Consequently this invention is easily applicable to any or all of the millions of card stencils now in daily use, and the clips may be made U-shaped and snapped on to the stencils.

Preferably such clips are adjustable on each stencil so that they may be moved by the operator into a position on each stencil such that it may momentarily close an electric circuit just before such stencil is advanced for use in a printing cycle, or it may be left in a position such that the selector actuating circuit will then be left open. Thus the operator can determine, in advance of the printing operation, as to which of the series of stencils in a stack thereof to be placed in the stencil magazine of the apparatus shall be used for printing and which shall be skipped; when the whole series are run through the machine, and then adjust the U-clips accordingly. When, however, this same mailing list is to be used again by running the same stack of stencils through the machine as before, any desired changes in the printing and/or skipping operation may be effected by correspondingly rearranging the clips on stencils for which such changes are required. Furthermore, inasmuch as the control device which is actuated by such selective means is reversible, as hereinafter shown, it is possible by a simple change in the position of a latch forming part thereof to cause skipping either of the stencils which close the selector actuating

circuit, or of those which leave said circuit open; and as a result of the conjoint use of these two features (the sliding clips and the reversing latch) a double flexibility of selection is obtained, with consequent advantages to be hereinafter explained.

The best form of apparatus at present known to me embodying my invention is illustrated in the accompanying three sheets of drawings, in which:

Fig. 1 is a perspective view of a card stencil blank equipped with an adjustable metal clip constituting one element of my invention.

Fig. 2 is a detail cross section on line 2—2 of Fig. 1; and Fig. 2a is a similar view of a modification.

Fig. 3 is a vertical section on line 3—3 of Fig. 4 showing certain parts of the machine portion of a stencil addressing apparatus embodying other features of my invention, parts being shown in section, and others omitted.

Fig. 4 is a perspective view of the same, parts being broken away and others omitted.

Fig. 5 is an enlarged detail cross section taken on line 5—5 of Fig. 4 showing the reciprocating finger of the selective mechanism.

Figs. 6 and 7 are detail side elevations of the reversible latch forming part of the mechanism for controlling the printing operation.

Fig. 8 is an enlarged detail section of the stencil magazine and stencil pusher, taken on line 8—8 of Fig. 4, looking from the other side of the machine, and

Fig. 9 is a detail side elevation of the reversible latch and cooperating mechanism.

Fig. 10 is a fragmentary plan view on an enlarged scale showing part of a stencil, with clip and guide therefor; and

Fig. 11 is a section on line 11—11 of Fig. 10.

Throughout the drawings like reference characters indicate like parts.

As also shown in my Patent No. 1,883,643, the machine portion of the apparatus comprises a reciprocating ink impression mechanism cooperating successively with a series of card stencils fed to it along parallel, oppositely grooved guides 30, by a constantly driven reciprocating stencil pusher 34. In the train of mechanism normally reciprocating the ink carrying member 42 of said impression mechanism is a latch 86 (Figs. 3, 4 and 9) which, when tripped, disables said reciprocating member with the result that a stencil is then passed through the printing zone without any printing being done from it. An electromagnetic controlling device for this latch 55

is selectively actuated by a pin or finger 8 pushed down on the frame 1 of each stencil *a* (Fig. 1) just before it enters the printing zone. The stencil frame, made of pasteboard or cardboard, has the usual shallow notch 3 along one edge already provided to enable the user to place all stencils in a stack A (Fig. 8) so that the characters cut in the thin panel 2 shall be right side up for reading when printed and for filing and indexing purposes, and in this notch, according to my present invention, I mount a U-shaped metal clip 4, the width of which is a little more than half the length of slot 3 so that it can be slid from one end of the slot to the other, the free ends of the 10 clip being bent toward one another as shown in Fig. 2, so as to overhang the inner edges of frame 1 and hold the clip thereon. The pin 8 strikes the stencil frame at about the point marked 18 in Fig. 1, if the clip is then in the 15 position there shown and the electric circuit is then not completed. Consequently the magnet 110 (Fig. 4) is then not energized. If, however, the clip is slid over point 18 the circuit through battery 16 (Fig. 3) wire 17 and the machine frame 5 to which it is connected, thence to one of the stencil guides 30, contact 31, clip 4, finger 8, selector bracket 5, and wire 13 fastened to the bracket by screw 14 is then completed through magnet 110, and the selective control device is 20 operated accordingly, as will be hereinafter described in detail.

The electrical contact 31 should preferably have an inclined upper face, as shown in Fig. 11, so tilted that the clip 4 may ride up on it without catching, when the stencil and clip are moving in the direction indicated by the arrow in Fig. 11. The notch 3 is deep enough to cause clip 4 to clear the stencil guide 30 and touch only contact 31, as shown in Fig. 10.

Clip 4 must have a length slightly greater than one-half the length of slot 3, so that the clips on adjacent stencils in the stack in a magazine will always overlap one another to a certain extent, as otherwise one clip might catch on another when the stencils are being pulled out of the 45 bottom of the magazine.

All the clips on all the stencils in any stack are located on one side of such stack so that it will tend to lean in the other direction as a result of the greater thickness of the clips, and so press against the other side wall of the magazine. To avoid this, I may apply a strip of paper or other cheap material 54 to one face of the other side of the stencil frame 1, as shown at 54, in Fig. 1. If this paper strip has a thickness about equal to double the thickness of the metal out of which clip 4 is made, it will compensate for the thickness of the two legs of each clip and even up the stack so that it will stand straight up. Also this 55 particular trouble may be avoided altogether by making the portion 111 of frame 1, which borders notch 3, sufficiently thinner than the rest of said frame to countersink the clip legs, as indicated in Fig. 2a. The strip 54 may then, of course, be omitted.

While I have shown clip 4 sliding longitudinally back and forth on the stencil frame, any other mounting for such a clip, which would permit it to be moved into or out of registration with the finger 8, could be substituted for that here shown.

As best shown in Fig. 5, finger 8 is slidably mounted in the finger holding frame 7 carried by slide 6 reciprocating vertically in bracket 5, which is insulated at 19 from the table 20 on which it is mounted and the remaining portions of the ma-

chine. A light spring 9 normally holds finger 8 with its shoulder 8a down against frame 7. A rack 10 on the back of slide 6 meshes with teeth on sector 11 pinned to shaft 12, and said slide is guided on the face of bracket 5, by retaining plate 15. Shaft 12 is oscillated by crank arm 163 (Fig. 4) connected by link 162 to crank arm 164 fast on shaft 104 journaled in housing 105 at the back of the machine. The shaft 104 is oscillated once in every cycle of printing operations with 10 the result that the magnet 110 is energized if finger 8 strikes a clip 4, as above described, or remains dead if said finger merely strikes the non-conducting frame 1 of stencil 2.

Other portions of the apparatus also shown in my Patent No. 1,883,643, above mentioned, may be described as follows: Below table 20 is located the power mechanism 22 which is of a type well known in the art unnecessary to describe further that serves to reciprocate the operating rod 24. The pair of spaced stencil tracks 30 are disposed above the table and extend lengthwise thereof and are adapted to guide successive stencils into and out of printing position. The collection of stencils A is contained in a stencil holder 32 which is located mainly above and at the right hand end of the stencil track and in line therewith (Fig. 4). A stencil pusher 34 of a well known type not necessary to describe and illustrate in greater detail is disposed below the pile 30 of stencils in the holder 32 and is arranged to be reciprocated under said pile to move the lowermost stencils successively out of the pile and into and along the stencil track 30.

A printing platen 36 is located beneath the stencil track and is supported by arms 38, see Fig. 3, which are pivoted to depending brackets 40 under the stencil table. A printing roll 42 is located above the stencil track and the platen and is journaled between rearwardly extended arms 44 which are connected to a horizontal yoke 46 pivoted on a horizontal shaft 48 carried by said bracket 40. Inking mechanism 50 of a well known type is located above the printing roll 42 and is adapted to supply ink thereto.

The inking roll and platen are adapted to be moved toward each other to press a stencil *a* against a sheet of paper, postcard or envelope placed beneath said stencil. To this end an arm 60 is pivoted on a shaft 62 carried by the depending brackets 40. Said arm 60 has an upstanding integral arm 64 which terminates in an upper cam face 66 that underlies a roller 68 carried by the platen arms 38 and is so arranged that when said arm 64 is rotated in a counter-clockwise direction, it raises the platen and holds it in an elevated position until the arm is restored to an inoperative position, as shown in Fig. 3.

The yoke 46 is integral with a depending arm 70 that is connected to the arm 60 through links 72, whereby both the platen and the printing roll are operated conjointly. The stencil pusher is operated conjointly with the platen and printing roll and all are operated by a vibrating arm 74, see Figs. 3, 4 and 9.

Said arm 74 is journalled on the shaft 62 and is pivotally connected with the upper end of the reciprocating actuating rod 24 so that said arm is reciprocated by said rod. The stencil pusher is operated by means of a link 76, Fig. 8, which is pivotally connected at one end with the stencil pusher 34 and at the other end with a forwardly extended arm 78 of a vertically pivoted hub 80. Said hub has a laterally extended 75

5 arm 82 at its lower end which is loosely received in a cam slot 84 of said arm 74 and carries an anti-friction roller 83 running in said slot. The arrangement is such that as said arm 74 is reciprocated vertically, the hub 78 is caused to be reciprocated about its vertical axis so as to reciprocate the stencil pusher.

10 Said arm 74 has a locking and releasing connection with the printing roll and platen so that it can operate the printing roll and platen when a selected stencil passes into printing position and can also reciprocate without operating the printing roll and platen, as hereinbefore indicated.

15 To this end the arm 60 of the printing mechanism, see Figs. 3, 4 and 9, is extended alongside the outer end of said arm 74 and carries at its outer end a pivotally mounted latch member 86. Said member has a tooth or projection 88 which 20 is adapted to enter a notch 90 in the outer face of said arm 74 under action of the tension spring 92 whereby to lock said arms 60 and 74 for conjoint reciprocatory movement. When the latch 76, however, is held out of engagement with said 25 arm 74, as illustrated, the arm 74 can reciprocate, without operating the arm 60, which remains motionless, with its stop lug 61 resting against strut 63, as shown in Fig. 3.

30 Selector mechanism is provided to control the latch member 86 and its connection with the arm 74. The selector control includes a vertically disposed latch-release arm 94 which is journaled in a depending bracket 96 carried by the rear edge of the table 20. Said arm 94 has a 35 depending extension 98 that is disposed in front of a roller 100 carried by an upper end of the latch member 86 and is adapted to engage said roller on movement in a counterclockwise direction, looking at Figs. 3 or 4, and effect disengagement of said latch member 86 from said arm 74. The release arm 94 is disposed in position to maintain said latch member 86 disengaged from the arm 74 when locked releasably in such 40 position by a latch 102 which is loosely carried 45 on a shaft 104.

The shaft 104 is reciprocated by means of a depending arm 166, see Fig. 9, the lower end of which is provided with a cam roller 168 which is located beside the outer end of the arm 74 and 50 in operative relation with the cam face 170 of a cam block 172 fixed to one side of said arm 74. The shape of said cam face 170 is such that when the arm 74 moves upwardly and is traversing the latter part of its range of movement, the arm 55 166 is permitted to move in a clockwise direction and thereby permit the spring 158 to oscillate shaft 104 and through linkage 164, 162, 163 raise the finger 8. During the downward movement of said arm 74 the reverse action takes place. If 60 the stencil a then under said finger has its clip 4 in a position to be struck by said finger, the electro-magnet is energized and (if the reversible latch 102 then has its notched face on the under side, as shown in Fig. 7) the arm 94 is 65 released to permit the connection between the latch member 86 and the arm 74, to take place or to continue if it has been established during the preceding cycle. On the next upward stroke of the arm 74, the release arm 94 is adapted to 70 be again restored to its normal position. To this end, the arm 94 is provided with a cam roller 174 which is adapted to be engaged by the inclined cam face 176 of a cam plate 178 carried by the arm 74. It is apparent that as said arm 75 74 is moved upwardly the cam face 176 will en-

gage the roll 174 and move the arm 94 in a counterclockwise direction (looking at Fig. 3) to restore it into holding engagement with the latch 102. The latch is reversible, being held by thumbscrew 103 in a housing 101 which is loosely mounted on shaft 104. The upper end of arm 94 is provided with a lower detent projection 106 and an upper one 107, which respectively cooperate with the latch 102 according to whether its hook shaped face is turned downward, as shown in Fig. 7, or upward as shown in Fig. 6. The armature for magnet 110 is mounted on one end of a trip lever 112 pivoted at 111 to bracket 96. The free end of this lever extends under latch housing 101, all as shown in Fig. 4. As 15 the magnet is energized when a stencil having its clip 4 in position to cooperate with finger 8 comes opposite the selector bracket, latch 102 will then be lifted. If theretofore it has been turned up so as to then engage detent 107, the 20 cam arm 98 of the swinging member 94-98 will be held out in position to trip latch 86, and no printing will be done as that stencil passes through the printing zone, because printing roll 42 will not move. If the next stencil has its clip 25 4 out of position to close the circuit, latch 102 will stay in its lower position, the member 94-98 will be free to swing under the pull of spring 108 so as to move its cam arm 98 out of the path of 30 latch roller 168, said latch will not be tripped 35 out of engagement with constantly reciprocating member 74, and a printing operation will be performed with that stencil. If, thereafter, the position of latch 102 is reversed so that it engages lower detent 106 only, the above described procedure will be reversed.

One advantage of this arrangement is that the selective operation on a whole series of stencils can be reversed at once, instead of it being necessary to go through the entire set and shift 40 the position of every clip 4, as would otherwise be necessary. Moreover, the combination of the two selective controls (reversible latch and adjustable clips) makes it possible to follow generally a uniform system for clip adjustment and 45 yet reverse that for a given set of stencils when necessary, without readjusting all the clips. Thus usually more stencils in a set are used for printing, than are skipped, so that a standard arrangement should be adopted by which the closing of the magnet circuit will cause a skipping of 50 the stencils which are to be skipped because then the electric portion of the apparatus will be used less, and possibilities of sparking reduced. This would require that clips on stencils to be skipped 55 shall be adjusted as shown in dotted lines in Fig. 1, so as to cover the point 13 on each stencil frame. All the stencils to be used for printing would then have their associated clips adjusted as shown in full lines in Fig. 1. To carry out such system the latch 102 would be turned up, as shown in Fig. 6. If, however, it was desired at any time to use all those stencils usually skipped, and skip those used at other times, a simple reversal of the latch 102 would accomplish that temporarily without 60 disturbing the regular arrangement of the clips according to the system above assumed to have been adopted. The only other way to secure such result would be to overhaul the entire set of stencils and shift each clip. This would be a 65 laborious job and a similar one would have to be done when that set was to be used again in the regular way. Moreover, the uniform system of clip arrangement above suggested would be 70 arranged.

- The advantage of the clip system over the one using holes in the stencil frame previously employed is that a clip can be easily snapped on to a standard card stencil, while the punching operation required elaborate punch mechanism and care in using it. Also the punched hole was unchangeable while the clip can be slipped into another position whenever the mode of use of the stencil carrying it is to be changed.
10. The advantage of mounting the clip in the notch 3 is that it does not then interfere with the stacking or feeding of the stencils. The electrical circuit closing action performed by the clip could be accomplished by other forms of circuit closing element so long as it was adjustable on the stencil into a position that would disable its circuit closing function. I believe that I am the first to thus adjustably mount on a stencil an element having a selective function causing printing or skipping 20 of the stencil according to its adjusted position.
- Having described my invention, I claim:
1. A stencil card having a shallow notch along a section of one edge, combined with a U-shaped clip of electrically conducting material mounted 25 on and movable along said notched edge section.
  2. A combination such as defined in claim 1 in which said stencil comprises a thin panel of stencilizable fabric and a surrounding rectangular frame of much thicker and stiffer material, 30 and in which said clip has its free ends bent toward one another over the inner edge of said frame.
  3. A card stencil having a border frame of electrically non-conducting material combined 35 with a clip of electrically conducting material arranged to grasp and move along one edge of said frame, overlaying at least one surface thereof; whereby said frame may be rendered electrically conductive over selected limited areas so over-laid.
  4. In a stencil printing apparatus comprising an ink impression mechanism, a card stencil, a grooved guide along which said stencil may be slid into the printing field of said mechanism, and means for either actuating or disabling said mechanism adapted to be selectively controlled by dissimilar features presented by successive stencils, the combination of a clip adjustable along the edge of such card stencil moving in 50 said guide groove, a member reciprocable toward and from said stencil to make or break contact with said clip if it has been adjusted in a predetermined position on said stencil, and an electrically operated device controlling said means for actuating or disabling said impression mechanism, one terminal of the circuit of which device is connected to said reciprocable member and the other to said guide, both of which are formed of electrically conducting material, but the stencil being 55 formed of non-conducting material, said reciprocable member being insulated from said guide.
  5. A combination such as defined in claim 4 in which said card stencil has a shallow notch in one edge of a length less than double the length of 60 said clip, and in which said clip is located in said notch.
  6. A combination such as defined in claim 4 in which said card stencil has in one edge a notch in which said clip is located, said notch being 65 deep enough to remove said clip from contact with the body of said grooved guide, but said guide being provided with a projecting electrical contact member located in the path of said clip.
  7. In a stencil printing apparatus comprising 70 an ink impression device, means for pushing a

stencil into operative relation with said impression device and power mechanism for transmitting motion to both said stencil pushing means and said impression device, but which can be automatically disconnected from the latter, the combination, of controlling means for said power mechanism capable of being actuated by said stencil, comprising a member which may be adjusted to either cause such stencil to be used in a printing operation, or to be skipped, with a device adjustable on such stencil for cooperating with said means.

8. A combination such as defined in claim 7 in which said power mechanism controlling means comprise an oscillating member elastically urged 15 to swing in one direction, and a latch actuated by said stencil adapted to engage said member and prevent it so swinging, or to leave it free to so swing, which said latch is reversible; whereby when said latch is in one position on its supporting member it will be moved out of engagement with said oscillating member when actuated by said stencil and so cause the same to be printed; but, when reversed, it will be moved into engaging position when thus actuated and so cause said 25 stencil to be skipped.

9. In an apparatus of the class described comprising a stencil pusher and a constantly reciprocating member for actuating said pusher, a printing mechanism, a latch for temporarily connecting said mechanism with said reciprocating member, a pivoted cam member operative to trip said latch when held in one position, a spring tending to move said cam member into another and inoperative position, and means for swinging said cam member into its first mentioned position once during each cycle of movement of said reciprocating member, the combination, with a second and manually reversible latch provided on one face only with means for engaging said cam 40 member and thereby hold it in said operative position, which second latch is movable on a fixed pivot the axis of which is substantially parallel to said face, of mechanism for automatically moving said last mentioned latch temporarily in the 45 direction toward which said engaging means face once during each cycle of movement of said reciprocating member and while said cam member is in the field of engagement with said last mentioned latch, which said mechanism is adapted 50 to be temporarily disabled once during each such cycle and while said cam member is in the field of its engagement with said last mentioned latch.

10. A combination such as defined in claim 9 comprising a guide along which card stencils may be pushed to said printing mechanism, and a card stencil equipped with means for selectively controlling said means for lifting said last mentioned latch.

11. A combination such as defined in claim 9 comprising a guide along which card stencils may be pushed to said printing mechanism, and a card stencil equipped with means for selectively controlling said mechanism for moving said last mentioned latch comprising a clip adjustably mounted on said stencil.

12. In a stencil printing apparatus of the type described including a stencil card, an ink impression mechanism and a device for disabling the 70 same, together with other mechanism for moving said stencil through said impression mechanism and adjustable means associated with said stencil enabling it, when said means is adjusted in one particular manner, to actuate said dis- 75

abling device while such stencil is passing through the printing zone.

13. A combination such as defined in claim 12 in which said disabling device comprises an element which, when properly adjusted, prevents said device from operating while the stencil associated with said so adjusted means is passing through the printing zone.

14. A combination such as defined in claim 12 in which said disabling device comprises an element which, when properly adjusted, prevents said device from operating while the stencil associated with said so adjusted means is passing through the printing zone but causes it to operate

when a stencil associated with differently adjusted means is passing through said zone.

15. A stencil card such as defined in claim 1 having a strip of material adhering to a portion of its frame opposite said notch, which strip has a thickness substantially equal to the sum of the thicknesses of the two leg portions of the U-shaped clip.

16. A stencil card such as defined in claim 1 which has a frame of substantially uniform thickness except along the section on which said clip is mounted, said section being sufficiently reduced in thickness to countersink said clip.

HARMON P. ELLIOTT.
